UNITED STATES PATENT OFFICE.

SIMON J. CONNELL, OF BROOKLYN, NEW YORK.

VALVE.

1,348,088.

Specification of Letters Patent. Patented July 27, 1920.

Application filed December 20, 1919. Serial No. 346,245.

To all whom it may concern:

Be it known that I, SIMON J. CONNELL, a citizen of the United States, and a resident of the city of New York, borough of Brooklyn, in the county of Kings and State of New York, have invented a new and Improved Valve, of which the following is a full, clear, and exact description.

This invention relates to improvements 10 in valves, and more particularly to a valve for steam traps, the purpose of the valve being to permit the exhaust of water of condensation when the latter reaches a predetermined level, an object of the invention 15 being to provide a valve which can be quickly assembled, which will maintain a tight closure except when moved to open position, and which will comprise but two main parts coupled together in an improved manner 20 and without employing nuts, bolts, or other removable devices for the purpose.

A further object is to provide a valve consisting of two members, one movable relative to the other and the members held in 25 operative position without the employment of a third part.

With these and other objects in view the invention consists in certain novel features of construction, and combinations and arrangements of parts, as will be more fully hereinafter described and pointed out in the claims.

In the accompanying drawings:

Figure 1 is a sectional elevation illustrating my improved valve in a steam trap;

Fig. 2 is an enlarged view in section on the line 2—2 of Fig. 1;

Fig. 3 is a view in section on the line 3—3 of Fig. 2;

Fig. 4 is a perspective view of one member of the valve;

Fig. 5 is a perspective view of the other member of the valve;

Fig. 6 is a sectional plan view illustrating 45 a modification; and

Figs. 7, 8, 9 and 10 are views illustrating another modification.

1 represents a steam trap having an inlet pipe 5 for conveying the water of condensation to the trap, and it is, of course, to be understood that my invention is not limited 50 to any particular form of trap as it may be utilized in connection with any well-known type in use.

55 My improved valve comprises two members A and B. The member A consists of a

tubular journal 2 having a screw threaded end 3 and a wrench receiving enlargement 4 adjacent the screw threaded end 3. The journal 2 is of cylindrical form and is provided with two longitudinal series of outlet ports 6. The free end of the journal is closed and made with a reduced extension 7 having an integral key 8 at its outer end. The member B comprises a fork 9 which is 60 integral with an arm 10 and circular bearing rings 11 are formed on the ends of the fork 9 and fit the journal 2. The rings 11 are connected by integral webs 12 which constitute valves and these webs have curved 70 inner faces curved concentrically with the journal and move on the surface of the journal so that they form, in effect, a ground joint and operate to close and open the ports 6 as seen most clearly in Fig. 3. The webs 75 12 are also tapering at their outer surfaces so that they present relatively sharp edges 13 which tend to cut any accumulated sediment or other material which may form on the outer face of the journal and therefore 80 maintain a clean valve seat to perfectly perform the function intended.

The free end of the arm 10 is screw threaded, as shown at 14, for the attachment of a float 15 so that the latter is caused 85 to move vertically by the water of condensation 16 which accumulates in the bottom of the trap. An integral elbow 17 is formed on one end of the fork 9 and is provided with a ring 18 to fit the extension 7 of the 90 journal 2. This ring 18 has a keyway 19 therein which permits the ring to move onto the extension over the key 8.

In order to position the member B on the member A, it is necessary that the member 95 B be in a vertical position which is a position that is never assumed by the normal operation of the device. After the member B is moved onto the member A, it is swung down into operative position and the key 8 100 serves to prevent disconnection of the two members. In operation, the float 15 causes the member B to turn on the member A and when the water reaches a predetermined level, the valves 12 open the ports 6 and 105 allow the water to escape. The float descends as the water escapes and causes the closing of the ports, as will be readily understood, to maintain the desired level in the trap.

In the modification illustrated in Fig. 6, 110 a hollow elbow extension 20 is made integral with the journal 2 and a screw threaded

nipple 21 is provided on the extension which is adapted to be projected through the wall of the trap. This modification enables a somewhat different assemblage from the preferred form, but in all essentials it is precisely like the preferred form.

It is obvious that my invention is not limited to any particular number of outlet ports or valves, but I find in practice that 10 two longitudinal series of ports with two valves is a preferred arrangement and performs all necessary functions.

In the modification illustrated in Figs. 7, 8, 9 and 10, I employ a strainer 22 which 15 may be of any desired formation and which comprises a cylindrical portion fitting around the rings 11 and the outer faces of the valves 12. The ends of the strainer 22 are flared outwardly, as shown at 23, and 20 are positioned under integral hooks 24 on the member B. These hooks 24 extend throughout the transverse dimension of the member and enable the strainer to be readily positioned therein when moved transversely 25 of the member or removed from the member whenever occasion may require. Furthermore, this form of connection permits the member B to carry with it the strainer so that whenever the coupling members are 30 disconnected, the strainer will be removed with the member B and does not interfere in any way with the operation of the parts.

To prevent accidental lateral movement of the strainer on the valve, a recess 25 is 35 provided in the upper hook 24 and an enlargement 26 is formed on the strainer which springs into this recess and prevents possibility of accidental displacement.

This strainer prevents any possibility of 40 waste or other material from plugging or entangling the valve, and, of course, can be used or not, as desired.

While I have described my improved valve in connection with a steam trap, it is 45 obvious that the invention is not limited to this particular use as the valve may be used for controlling, throttling, or regulating water, steam, gas, air, oil or other fluids, and vapors, and may be operated by means 50 of a float, as shown, or by means of any other movable element which is applicable for any of the uses above indicated.

Various other slight changes may be made in the general form and arrangement 55 of parts described without departing from the invention, and hence I do not limit myself to the precise details set forth, but consider myself at liberty to make such changes and alterations as fairly fall within the spirit and scope of the appended claims.

I claim:

1. A valve of the character described, comprising two members, one member consisting of a tubular journal having ports therein, a 65 reduced extension on one end of the tubular

journal, a key on the extension, the other of said members having rings fitting the journal, webs connecting the rings and comprising valves controlling the ports, and a ring on the last-mentioned member fitting the extension and having a keyway therein movable over said key. 70

2. A valve of the character described, comprising two members, one member consisting of a tubular journal having ports therein, 75 an integral extension of reduced diameter on the end of the journal, a key on said extension, the other member comprising a fork, rings on the ends of the fork fitting the journal, webs connecting the rings and 80 constituting valves controlling the ports, an angular extension on the fork, and a ring on the angular extension fitting the extension of the journal and having a keyway therein movable over the said key. 85

3. A valve of the character described, comprising two members, one member consisting of a tubular journal having ports therein, an integral extension of reduced diameter on the end of the journal, a key on said extension, the other member comprising a fork, rings on the ends of the fork fitting the journal, webs connecting the rings and constituting valves controlling the ports, an angular extension on the fork, a ring on the angular 95 extension fitting the extension of the journal and having a keyway therein movable over the said key, and a float carrying arm integral with the fork. 99

4. A valve of the character stated, comprising two members, one member comprising a tubular journal having ports therein, said journal having a screw threaded end, a wrench receiving enlargement on the journal, a reduced extension on one end of the 105 journal and a key on the extension, the other member mounted to move on the journal, valves on the last-mentioned member controlling the ports, and a keyway in the last-mentioned member permitting the insertion 110 and removal of the last-mentioned member on the first-mentioned member. 110

5. A valve of the character described, comprising two members, one member consisting of a tubular journal having a port therein, the other member having turning movement on the first-mentioned member and controlling said port, and a strainer around the last-mentioned member. 115

6. A valve of the character described, comprising two members, one member consisting of a tubular journal having a port therein, the other member having turning movement on the first-mentioned member and controlling said port, said last-mentioned member having hooks thereon, and a strainer positioned around the last-mentioned member and having its ends located under the hooks. 120

7. A valve of the character described, comprising two members, one member consisting 130

of a tubular journal having ports therein, the other member comprising a fork, rings on the ends of the fork fitting the journal, webs connecting the rings and constituting 5 valves controlling the ports, and a removable strainer fitting around said rings and webs.

8. A valve of the character described, comprising two members, one member consisting 10 of a tubular journal having ports therein, the other member comprising a fork, rings on the ends of the fork fitting the journal, webs connecting the rings and constituting valves controlling the ports, hooks on the 15 fork, one of said hooks having a recess therein, a strainer fitting around the rings

and the webs and having outwardly flared ends removably located under the hooks, and means preventing lateral movement of the strainer on the member. 20

9. A valve of the character described, comprising two members, one member consisting of a tubular journal having a port therein, the other member having rotary mounting on the journal, a valve on the last-mentioned 25 member adapted to cut off said port and control the passage therethrough, and said members having key and keyway interlocking engagement holding said members against independent longitudinal movement. 30

SIMON J. CONNELL.
